ATTORNEY

UNITED STATES PATENT OFFICE

149,625

DESIGN FOR A DARNER

Rolf J. Falk, Zanesville, Ohio, assignor to Shawnee
Pottery Company, Zanesville, Ohio, a corpora-
tion of Ohio

Application June 5, 1947, Serial No. 139,456

Term of patent 14 years

(Cl. D3—19)

To all whom it may concern:

Be it known that I, Rolf J. Falk, a citizen of the United States of America, residing at Zanesville, in the county of Muskingum and State of Ohio, have invented a new, original, and ornamental Design for a Darner, of which the following is a specification, reference being had to the accompanying drawings, forming a part thereof, wherein:

Fig. 1 is a front elevational view of a darner, illustrating my new design;

Fig. 2 is a side elevation; and

Fig. 3 is a rear elevation.

I claim:

The ornamental design for a darner, as shown.

ROLF J. FALK.
